UNITED STATES PATENT OFFICE.

RICHARD VON REPPERT, OF HARTFORD, CONNECTICUT, ASSIGNOR TO UNDERWOOD
ELLIOTT-FISHER COMPANY, OF NEW YORK, N. Y., A CORPORATION OF DELAWARE.

TYPEWRITING MACHINE.

Application filed July 1, 1927. Serial No. 202,792.

The present invention relates to type-writing machines and more specifically to type-bar actions of that class where the depression of the key operates through intermediate connections to lift the type-bar from its pad and project the type-end against the front face of the platen to type.

Machines of this character, which have obtained commercial supremacy, depend upon the staccato blow at the key to drive a type-head under a momentum, augmented by accelerating connections, to strike the face of the platen the quick, sharp blow that develops the noisy click so objectionable in any place where the machines are in use.

One feature of the present invention employs a standard type-bar swingable from a horizontal state of rest, upwardly and rearwardly to strike the front face of a case-shiftable platen to type in either lower or upper case characters; the type-bars being uniformly arranged in radial planes, mounted as a series upon a pivot-wire carried by a vertically-disposed radially-slotted segment in a conventional manner. Each type-bar includes the unit-assembly of connected parts forming a succession of toggles, one end of one toggle connecting with the type-bar and the other end thereof pivotally anchored to the frame. These connecting parts co-operate to lift the type-bar from a pad to the platen by a decelerating translation of motion, due to the straightening out of the toggle-elements at the instant of the type-impact at the platen. These connections per se promote an easy but slow movement of the type-bar of great power, and, at the instant of type-impact, the straight-line positions assumed by the parts serve to retard and arrest any momentive energy in the type-head, which results in a pressure-impact of the type-face against the platen instead of a sharp blow. To preserve these features and speed up the transmitted accelerated effect upon the type-bar's motion, accelerating elements intermediate the keys and the type-bar lifting linkages are employed so that, as the decelerating effect on the type-bar decreases the speed of its movement, the accelerating effect of the key-lever movement increases the speed of the lifting linkages, and the resultant is a light, snappy, compressing type-bar movement that makes its typing impact quietly and positively

without the noisy transformations of momentum into typing force.

Another feature includes the preassembly of the type-bar and its connected decelerating lifting linkages as a unit, which units may be assembled into the machine upon segment-wires for fulcrums with each assembled unit assuming the same radial plane predetermined for the type-bar towards a common typing center that provides for a straight line of transmission from its pivotal anchorage on the frame. Each type-bar linkage has a key-actuated means that includes a pair of accelerative rolling or wiping contact bell-crank levers, one bell-crank positioned directly over its associated key-lever for a vertical straight-line pull, and the other bell-crank aligned vertically to the first bell-crank to coact therewith while the free ends thereof, as a series, progressively vary in height to align with a pivotal point on its associated linkage-member of the type-bar for a straight-line transmission of power through a link that is self-adjustable to the vertical planes of the bell-cranks and the radial planes of the type-bar linkages. The whole train of transmission from the key-lever to the type-bar being laid off along straight lines as with four banks of straight parallel key-levers, forty-two straight-line, radial type-bar linkages and straight-line transmissions of motion from part to part provide a type-bar action that is practically free of side stresses so common in front-strike type-bar actions where a toggle-action operates to raise a type-bar to type.

Other features and advantages will hereinafter appear.

In the accompanying drawings,

Figure 1 is a vertical skeleton lay-out of the type-bar at the middle of the segment, the type-bar and connections being shown in normal positions in full lines, and in typing positions in dot-and-dash lines.

Figure 2 is a detail view of the extreme outside bell-crank, its key-actuated lever and its link-connection to extreme outside bar-linkage.

Figure 3 is a vertical cross-section through the frame looking from the front of the machine, showing the relation of the key-levers and bell-cranks to the radial positions of the type-bars and their linkages.

The keys 10 are arranged in four banks and each key provided with a key-lever 11 that assumes the form of a U, one leg thereof, as 12, forming the stem of the key and 5 the other leg, as 13, terminating at a horizontal fulcrum-wire 14 mounted in the frame 15 of the machine. The key-levers 11 are disposed in parallel planes and spaced off at their rear ends by slots 16, while a 10 front comb 17 provides a forward guide for the up-and-down movement of the keys. This U-shaped formation of the key-levers, taken as a series, forms a transverse pocket within which an actuating mechanism for 15 the type-bars is arranged, in condensed relation, to reduce the height of the machine, and further provides that the vertical dip of the keys 10 shall be practically in straight lines through the elevation of the fulcrum 20 14 to the horizontal plane of the keys, and hence there is less interference between the depressed key and the adjoining keys, as heretofore, where the fulcrum is at the rear end of a straight key-lever.

25 Between the two side walls 18 of the frame 15, and adjacent the top edges of the key-levers 11, there may be secured a straight cross-bar 19 having open slots 20 cut crossways of the bar at the upper edge, 30 with the slots spaced and aligned to the key-levers 11. Preferably at the rear face of the bar 19 a slot 21 is cut longitudinally of the bar to provide for the entrance of a fulcrum-rod 22 that may be secured therein 35 by suitable screws threaded into the bar to bear upon the ends of the rod. Within each slot 20 a sub-lever, having two arms 23 and 24, is assembled and held therein for a free 40 rocking movement by the fulcrum-rod 22 passing through a perforation of the lever. This sub-lever may be formed of sheet metal to provide that the edge of the arm 23 thereof be bent over at right angles to form a flat 45 arcuate face 25 to serve as a tread for purposes to appear. The arm 24 may be pivotally connected to a link 26 pivotally secured to a key-lever at 27.

A bar 28 may be secured to the side walls 18 to lie parallel to the bar 19 and formed 50 with open slots 29 and slotted longitudinally to receive a fulcrum-rod 30 secured therein in a manner described for the rod 22. Within each slot 29 a bell-crank 31 is assembled to rock upon the fulcrum-rod 30, 55 and each bell-crank includes two arms 32 and 33. The arm 33 has an arcuate-edge formation 34 to bear against and be wiped by the arcuate face 25 of the arm 23. The relation between these two arms 23 and 33 60 provides for an acceleration of motion between the two arms in a well-known manner. A suitable spring 34a may be provided to restore each key-lever to a normal position against a pad 35.

65 36 indicates a segment-bar secured at the

ends thereof to the side walls 18 and having slots 37 cut across the front face thereof that radiate from a common point at or just under the typing position. The front face is further provided with an arcuate slot 38 70 to receive a curved fulcrum-wire 39 secured therein in the usual manner. Within each slot 37 there is assembled to pivot upon the wire 39 a pair of links 40 having a combined thickness to fill the slot for a free rocking 75 movement. These links 40, after leaving the segment-bar 36, are offset or spread apart to embrace a lever 41 at their upper ends, the lever being swingable upon a shouldered stud 42 that also binds the free 80 ends of the two links together.

43 indicates a segment-bar slotted radially across its rear face and provided with a curved fulcrum-wire 44 upon which and within said slots there is assembled one end 85 45 of a T-shaped lever having two other arms 46 and 47 depending from said fulcrum-wire. The arm 46 is pivotally secured to one end of the lever 41, and the free end of the arm 47 is pivotally secured between 90 two links 48, as upon a shouldered stud 49, that serves to bind the ends of the links together and provide a bearing for the arm 47. The opposite ends of the two links 48 are pivotally secured to a type-bar 50 by a similar stud 51.

The entire type-bar 50 is preferably made from sheet metal and takes the form of a truss that includes the straight member 52 joinable at both ends to angular members 100 53, forming an apex at the point of the connection 51 to the links 48 and reinforced by a tie-bar 54 that assumes a position substantially in line to the line of pressure from the actuating links 48 when the type-bar is at 105 a typing position, to prevent any spring of the open type-bar as it makes its impression under pressure. The outer end of the type-bar may be provided with a plurality of types 55 and may normally rest upon a sound-deadening pad 56 supported by the segment 43. The inner end of the type-bar may be perforated to receive a fulcrum-rod 57 mounted in a slot 58, and each type-bar 110 guided to a common printing point by the sides of the radial slots 59 cut across the front face of the segment 60 in a well-known manner. The type-bars have a working fit within the slots 59 to provide a free swinging movement of the bar, and, to stabilize 115 the type-head at the instant of the type-impression, a stationary type-guide 61 may be secured to the frame of the machine. The type-bars all swing about the stationary fulcrum-rod 57, and, to provide for the typing of each type-face thereon, a platen 62 120 may be case-shifted in any well-known manner.

It will be noted that the bars 36, 43 and 60 are segments, all having a curvature con- 130

centric to a common typing position on the platen, and that the bars 19 and 28 are horizontally disposed, and the levers 23—24 and the bell-cranks 32—33 are arranged therein 5 in planes parallel to the key-levers 11; that, as the position of the type-bar and its intermediate connection to the links 40 climb the sides of their segments from the middle position at Figure 1, the length of the arm 32 10 progressively increases to the length shown in Figure 2, where the arm 32^a indicates the height for an extreme side type-bar, and that the arm 24 is correspondingly lengthened at 24^a to provide for the equalization 15 of transmitted motion from a uniform dip of the key-lever to the positions of the segmental type-bars.

It is an advantage that the type-bars and 20 all the connections to the links 40 be uniformly the same and that the pivotal connections 63 to the links 40 be uniformly the same distance from the fulcrum-wire 39 for all the links for production purposes and to 25 avoid confusion in assembling. It is also an advantage to provide a single adjustment between two of the parts to compensate for variations in manufacture. To this end, an 30 adjustable connection is provided between the links 40 and the arms 32 of the bell-cranks that includes a rod 65 flattened at 35 and perforated at the end to pivot upon a shouldered stud between the two links 40, as indicated at 63, and a threaded screw end 67 to enter a threaded hole in the end of a 40 spring-clip 68 and arranged in a well-known manner to snap into a perforation in the free end of the arm 32. The threading of the screw 67 into the clip 68 provides an adjustable connecting means which provides that 45 the type-bars may be adjusted to lie upon the pad 56 and the key-levers 11 be spring-pressed against the pad 35 without vibratory tensions in the intermediate connections.

50 It will be noted at Figure 3 that the arms 32 assume vertical parallel planes and that the pivotal position 63 on the links 40 bisects these planes at points that are radial to the typing position; hence, the pull of the connections 64 is in straight lines, and the usual manner of offsetting or fanning the upper ends of the arms 32 to bring these two points into alignment is avoided. Furthermore, the sections 66 of the connections 55 having a free turning movement through the screw 67 turning within the clip 68, the connections become self-adjusting between the vertical planes of the arms 32 and the radial planes of the links 40.

60 It will be further noted that there is no positive connection between the two arms 23 and 33, so that the key-levers 11 may be restored by their springs 34^a independently of the return of the links 40 under the tension of their springs 69.

When a key 10 is depressed to rock its lever 11, the connection 26 vibrates the arm 24 to rock about the fulcrum 22 to rock the arm 23, while the arcuate tread 25 engages the arm 33 of the bell-crank at a bearing 70 point near the fulcrum 22 and distant from the fulcrum 30, and, as the arm 23 rises to the dotted position of Figure 1 for the end of the key-stroke, this bearing point between the two arms 23 and 33 progressively 75 creeps towards the fulcrum 30 of the arm 33 and away from the fulcrum 22 of the arm 23, transmitting a well-known form of accelerating motion to provide an easy initial movement of the key-lever to convey motion 80 to a train of inert parts. The rocking of the arm 32 pulls upon the links 40 to vibrate the upper ends thereof to drive the lever 41, T-lever 45—47 and links 48 to lift the type-bar to its typing position. During this 85 movement of lifting the type-bar, the arm 47 and link 48 become toggle-elements which, in straightening out, lift and project the type-bar and finally, as the bar acquires its greatest momentum at the typing position, the straightening out of a toggle retards and decelerates the type-bar against its 90 momentum and transmits a relatively great printing pressure but at a low velocity.

95 The type-bar performs the printing operation by pressure instead of impact, and, to avoid any tendency of the type-faces to blur during the typing instant, the arms 32 may be arrested by contact with a bumper or resilient pad 70 secured to the bar 28, and the sudden checking of these arms by the pad conveys a catapult reaction to the intermediate connections to the type-bar to further accelerate the movement of the type-bar approximately at the instant of typing, and this reaction may be further augmented by providing the free end of each lever 41 with a weight 71 whose rotary momentum is converted into a straight-line pressure to the 100 lever 45—47 and the type-bar.

105 After the toggling elements have been brought to a state of rest, as indicated by dot-and-dash lines in Figure 1, there are reactionary forces brought into play to break the toggle due in part to the sudden checking of the arms 32 by the pad 70 and the recoil of the weight 71, and by the springs 69, to quickly remove the type from the typing position.

110 It will be noted that the type-actions are controlled from a standard keyboard with a single case-shift; but operating motion is transmitted to each type-bar from a uniform touch and dip of the keys; that each type-bar is provided with a lifting toggle that becomes straightened out at the typing position; that the type-bar-lifting toggle is actuated by an intermediate toggle that becomes straightened out in straightening out 115 the first toggle; that both toggles are aligned 120

to the same radial plane as their associated type-bar for a straight-line transmission of motion; that intermediate radially-disposed toggles are actuated by accelerating bell-crank 5 cranks arranged in vertical parallel planes that bisect the planes of the toggles at a uniform radial point for a uniform transmission of leverage and in approximately a straight line; that each type-bar and its two connecting toggles may be assembled as a stock unit and assembled radially to their 10 segments as units; that the key-levers and accelerating members are aligned in parallel vertical planes predetermined by a standard 15 spacing of the keyboard; and that the key-levers are U-shaped with a pivot at one end and a key at the other to provide for a substantially straight up-and-down movement of the key in typing without the interference 20 from adjoining keys so manifest in the usual four-bank keyboard.

Variations may be resorted to within the scope of the invention, and portions of the improvements may be used without others.

25 Having thus described my invention, I claim:

1. In a front-strike typewriting machine having a series of horizontally-disposed type-carriers swingable upwardly and rearwardly to type from a vertically-disposed radial segment, and a series of parallel horizontal key-levers therefor, the combination of mechanism for conveying motion from the horizontal key-levers to swing the vertically-radial striking type-carriers, including a pair of connected toggling linkages aligned to the swinging plane of its type-carrier, one toggle operative to swing the type-carrier to type and another toggle operative to drive the first toggle, and mechanism supported upon straight horizontal supports and connecting the key-levers and the driving toggles, including bell-crank 30 driven one way by the key-levers and permanent connections from the bell-crank to the driving toggles.

2. In a front-strike typewriting machine having a series of horizontally-disposed type-carriers swingable upwardly and rearwardly to type from a vertically-disposed radial segment, and a series of parallel horizontal key-levers therefor, the combination of mechanism for conveying motion from the horizontal key-levers to swing the vertically-radial striking type-carriers, including a pair of connected toggling linkages aligned to the swinging plane of its type-carrier, one toggle operative to swing the type-carrier to type and another toggle operative to drive the first toggle, and mechanism pivotally supported in straight uniform planes and connecting the key-levers and the driving toggles, including vertical bell-crank 35 driven by key-lever-actuated 40 one-way accelerating connections and uni-

form horizontal connections from the bell-crank to the radial driving toggles.

3. In a front-strike typewriting machine having a series of horizontally-disposed type-carriers swingable upwardly and rearwardly to type from a vertically-disposed radial segment, and a series of parallel horizontal key-levers therefor, the combination of mechanism for conveying motion from the horizontal key-levers to swing the vertically-radial striking type-carriers, including a pair of connected toggling linkages aligned to the swinging plane of its type-carrier, one toggle operative to swing the type-carrier to type and another toggle operative to drive the first toggle, and mechanism intermediate the key-levers and the driving toggles pivotally supported in straight uniform planes and including vertical bell-crank 45 swingable about a straight universal horizontal axis to be actuated by accelerators arranged in planes parallel to the bell-crank and having connections with the key-levers, and horizontal connections of a uniform length between each bell-crank to a driving toggle.

4. In a front-strike typewriting machine having a segmental series of horizontally-disposed type-carriers swingable upwardly and rearwardly to type and a series of key-levers therefor, the combination of mechanism for conveying motion from the key-levers to swing the type-carriers, including a train of connected radially-disposed toggling linkages for each type-carrier, one toggle operative to swing the type-carrier to type and another toggle operative to drive the first toggle, and mechanism intermediate the keys and the driving toggles, including vertical bell-crank 50 horizontal connections from each bell-crank to a driving toggle and a sub-lever intermediate the bell-crank and connected to the keys.

5. In a front-strike typewriting machine having a segmental series of horizontally-disposed type-carriers swingable upwardly and rearwardly to type and a series of key-levers therefor, the combination of mechanism for conveying motion from the key-levers to swing the type-carriers, including a train of connected radially-disposed toggling linkages for each type-carrier, one toggle operative to swing the type-carrier to type and another toggle operative to drive the first toggle, and mechanism intermediate the keys and the driving toggles, including vertical bell-crank 55 horizontal connections from each bell-crank to a driving toggle and a sub-lever intermediate the bell-crank and connected to the keys, said sub-levers having a one-way connection to the bell-crank, including motion-accelerating wiping faces.

6. In a front-strike typewriting machine having a segmental series of horizontally-

- disposed type-carriers swingable upwardly and rearwardly to type and a series of key-levers therefor, the combination of mechanism for conveying motion from the key-levers to swing the type-carriers, including a train of connected radially-disposed toggling linkages for each type-carrier, one toggle operative to limit the typing movement of the type-carrier and another toggle operative to drive and limit the movement of the first toggle, and mechanism intermediate the keys and the driving toggles, including vertical bell-cranks of varying lengths and horizontal connections of uniform lengths between the bell-cranks and the driving toggles.
7. In a front-strike typewriting machine having a segmental series of horizontally-disposed type-carriers swingable upwardly and rearwardly to type and a series of key-levers therefor, the combination of mechanism for conveying motion from the key-levers to swing the type-carriers, including a train of connected radially-disposed toggling linkages for each type-carrier, one toggle operative to limit the typing movement of the type-carrier and another toggle operative to drive and limit the movement of the first toggle, mechanism intermediate the keys and the driving toggles, including vertical bell-cranks of varying lengths and horizontal connections of uniform lengths between the bell-cranks and the driving toggles, and means to jointly arrest the typing stroke of the keys and the driving movements of the bell-cranks to arrest the driving toggles at the impact of the types in typing.
8. In a front-strike typewriting machine having a segmental series of horizontally-disposed type-carriers swingable upwardly and rearwardly to type and a series of key-levers therefor, the combination of mechanism for conveying motion from the key-levers to swing the type-carriers, including a train of connected radially-disposed toggling linkages for each type-carrier, a toggle operative to swing the type-carrier to type, another toggle operative to drive the first toggle and both toggles operating to decelerate the movement of the type-carrier towards the typing position, and mechanism intermediate the keys of the driving toggles operative to accelerate the movement of the type-carrier, including bell-cranks having link-connections to the driving toggles and sub-levers connected to the key-levers, each sub-lever having a wiping tread to engage its associated bell-crank.
9. In a front-strike typewriting machine having a vertically-disposed segment with a series of type-carriers swingable upwardly and rearwardly to type and a series of horizontally-disposed key-levers therefor, the combination of means for conveying motion from the key-levers to the type-carriers, a pair of vertically-disposed segments below the type-carrying segment, toggle-links anchored to one segment and connected to each type-carrier, other toggle-links anchored to the other segment and connected to drive the first-mentioned toggle-links to lift the type-carrier, and connections between each driving toggle and a key-lever.
10. In a front-strike typewriting machine having a platen, a swingable type-carrier and a key-lever therefor, the combination of mechanism connecting the type-carrier and the key-lever for typing, including a pair of co-operating buckled-up toggles to be straightened out, one toggle operatively connected to swing the type-carrier when straightened out and an actuating toggle operative to straighten out the first toggle when said actuating toggle is straightened out, and mechanism intermediate the key and the actuating toggle, including a bell-crank having a link-connection to said toggle and operatively connected to the key.
11. In a front-strike typewriting machine having a series of segmental type-carriers pivotally disposed for a standard radial spacing to type at a common center and a keyboard of standard form having key-levers disposed in horizontal, straight, parallel planes from the keys, the combination of means for conveying motion from each key-lever to its associated type-carrier by straight-line transmissions without side stresses, said means including a decelerating linkage mounted to assume the same radial plane of the type-carrier, accelerating bell-cranks vertically disposed in the planes of the keys, horizontal connections between each bell-crank and its linkage, the relative elevation of each connection being predetermined by the position of the type-carrier on the segment, and connections between the key-levers to variably accelerate different bell-cranks to actuate each type-carrier uniformly from a uniform dip of the keys.
12. In a type-bar action for a typewriting machine having a series of parallel horizontal key-levers and a series of horizontally-disposed pivoted type-bars swingable upwardly and rearwardly to type, the combination of motion-transmitting mechanism intermediate the key-levers and the type-bars, including accelerating elements connected to each key-lever and swingable in the plane of said lever, and a pair of decelerating toggles cooperative in connecting the accelerating elements with a type-bar and swingable in the radial plane of said type-bar, the accelerating and decelerating elements providing separate straight-line motions that co-operate at a point determined by the segmental angle of the type-bar.
13. In a type-bar action for a typewriting machine having a series of parallel horizontal key-levers and a series of horizontally-

disposed pivoted type-bars swingable upwardly and rearwardly to type, the combination of motion-transmitting mechanism intermediate the key-levers and the type-bars, 5 including accelerating elements connected to each key-lever and swingable in the plane of said lever, a pair of decelerating toggles co-operative in connecting the accelerating elements with a type-bar and swingable in the 10 radial plane of said type-bar, the accelerat-

ing and decelerating elements providing separate straight-line motions that co-operate at a point determined by the segmental angle of the type-bar, and a connection between the two straight-line moving elements operative 15 to compensate for the varying angles of the type-bars for a non-side-stressing translation of power in driving a type-bar to type.

RICHARD VON REPPERT.
